METHOD OF MAKING THREADED LOCKING DEVICES

Richard W. Luce, Southport, Conn.

Application February 5, 1943, Serial No. 474,765

7 Claims. (Cl. 10—86)

1

The invention herein disclosed relates to a method of making a threaded locking device of the type disclosed in my co-pending application, Serial No. 322,650, filed March 7, 1940, for Threaded locking device, and this application constitutes a division of that application.

An object of this invention is to provide a method for making lock nuts in which the locking force is exerted by a resilient element normally maintaining two axially spaced threaded portions with the threads thereof out of phase. Another object of the invention is to provide a simple, practical and efficient method for this purpose.

The foregoing objects and certain advantages that will hereinafter appear, are realized in the method that is described in detail below in conjunction with the accompanying drawings in which:

Fig. 1 is a plan of a formed blank for a lock-nut embodying the invention;

Fig. 2 is an elevation, partly in section of the same;

Fig. 3 is a plan of the blank after further fabrication;

Fig. 4 is a side elevation of the same;

Fig. 5 is a plan of a completed lock-nut;

Fig. 6 is an axial section thereof;

Fig. 7 is a plan view of a modified form of lock-nut;

Fig. 8 is a longitudinal section of the same;

Fig. 9 is a plan of another modified form of the lock-nut; and

Fig. 10 is a longitudinal section of the same.

The blank illustrated in Figs. 1 and 2 includes a hexagonal body portion 1 and a cylindrical extension 2 at one end of the body portion. The body portion is bored as at 3 and the cylindrical extension 2 is a wall section of considerably less thickness than the thickness at the body portion 1. The cylindrical portion extends from adjacent the outer edge of the body portion of the nut.

The same blank is illustrated in Figs. 3 and 4. After the blank of Fig. 1 has been machined, the wall section of the cylindrical portion 2 is notched as at 4. In the blank illustrated, the wall section 2 is notched at six places equally spaced angularly about the axis of the nut. This notching is accomplished during the construction of the nut by a punch which moves in radially of the axis of the nut and shears the metal along the edge of the notches in the manner of a punch press. The notching of the wall section 2 provides, in the illustrated blank, six strips 5 equally spaced through equal angles about the axis of the nut. These strips constitute the wall section of the

2

extension 2 in the blank after the notching operation.

After the extension 2 has been notched, the strips 5 are rolled or peened over so that they are reversely bent as illustrated in Figs. 5 and 6. They are rolled inwardly and the notching is such that the outer edges of the strips are caused, when the strips are reversely bent, to form a substantially continuous overhanging portion 6 having substantially the same internal diameter as the body 1 of the nut. The bent portion 7 of the strips 2 form a wall section that constitutes a resilient portion uniting the body portion 1 of the nut and the portion 6 axially aligned with the body portion.

After the strips have been rolled over to the shape illustrated in Figs. 5 and 6, the nut is tapped. The tap is run through the body portion 1 and the axially aligned portion 6 formed by the wall section 2. Subsequent to the tapping operation, the nut is compressed to move the aligned threaded portion 6 towards the body portion and to position the aligned portion with the thread thereof out of phase with the thread of the body portion.

The relation is illustrated in the nut in Fig. 6. The amount of metal in the wall section constituting the resilient portion 7 of the nut is such that the section 7 has a resiliency so that the two threaded portions may be moved relatively in an axial direction an amount greater than the ordinary commercial thread tolerances, without the resilient portion losing its ability to effectively exert a locking force. It is to be noted, that the relation of the several portions of the nut are

such that upon relatively axial movement of the threaded portions the resilient portion partakes of a bending action.

When the nut is threaded on the bolt, the bolt first enters the body portion and then passes to the aligned threaded portion 6. The aligned threaded portion 6 is moved by the bolt axially, and relatively to the body portion 1, until the thread of the aligned portion 6 is brought into such position that the thread of the bolt may enter into engaging relation with the thread thereof. This movement effects a bending action in the wall section constituting the resilient portion which tends to return the aligned portion 6 to its normal out of phase position. This tendency of the resilient portion 7 causes the thread of the body of the nut to be drawn into surface engaging and frictional contact with the thread of the bolt entered therein. The forces so exerted by the resilient portion and the frictional engagement of the surfaces of the threads thus caused

is sufficient to prevent rotation of the nut on the bolt under action of forces resulting from vibration and shock ordinarily encountered in service.

The nut illustrated in Figs. 7 and 8 likewise includes a body portion 8 having the load-carrying threads therein, an aligned tapped portion 9 and a resilient portion 10. In this nut, the rolled over wall section forming the resilient portion 10 and the aligned tapped portion 9 is continuous or unbroken. It is, however, reduced in thickness at the section forming the resilient portion.

In making this nut the cylindrical extension of a blank such as that illustrated in Figs. 1 and 2 is rolled over as indicated in Fig. 7. The wall of the extension is of a thickness sufficient to receive a thread and form a continuous threaded section. After the extension is rolled over the wall section of the resilient portion is of a thickness indicated by the broken line 11. An axial moving, form-cutting tool is utilized to reduce the wall section of the resilient portion by removing the portion between the broken line 11 and the solid line of the resilient portion 10. Next the nut is tapped, the tap being run through the body portion and the aligned portion 9. Then the nut is compressed axially to throw the thread of the aligned portion out of phase with the thread of the body portion. The thickness of the wall of the resilient portion 10 is reduced as above described an amount to provide the desirable resiliency.

As the turned in portion of the extension is reduced in diameter, the wall thickens. Thus, the wall section of the extension may be made thinner than that required to hold a thread and the inturned portion will be thick enough to hold a thread.

In Figs. 9 and 10, a nut is illustrated in which the resilient portion is slotted after the cylindrical extension has been rolled over. This nut includes a body portion 12, an aligned tapped portion 13 and a resilient portion 14. The resilient portion consists of a series of strips 15 symmetrically disposed about the axis and extending between the body portion and the aligned tapped portion.

A blank such as that illustrated in Figs. 1 and 2 is utilized in making this nut. The cylindrical extension is rolled over to form the aligned portion 13. After the cylindrical extension is rolled over, a series of cutters are moved in radially, cutting a series of slots 16 and thus forming the strips 15 that make up the resilient portion. The nut is then tapped and compressed to throw the threads of the two tapped portions out of phase.

When a bolt is entered in the finished nut, it is threaded through the body portion and engages the aligned threaded portion. The bolt forces the aligned threaded portion away from the body of the nut until the thread thereof is brought into position to engage the thread of the bolt. The resilient portion, which is expanded, partaking of a bending action, endeavors to re-establish the normal out-of-phase relation of the two threaded portions and in so doing effects a force which causes the thread of the body portion to engage in frictional engagement with the thread of the bolt. It is to be noted that in each instance the thread engagement of the body portion of the nut with the thread of a bolt entered therein is in the same direction as that which would be effected by a force applied to the engaging face of the nut.

The several nuts illustrated in the drawings are of a kind that may be classified as "rolled over" nuts. In each of the constructions, there is

formed a cylindrical extension on the end of the body of the nut. This extension is rolled over to form the resilient portion and the smaller tapped portion. The metal of the resilient portion is reduced in various ways to secure the desired resiliency.

From the foregoing description of the making of the threaded locking devices illustrated in the drawings, it will be seen that by this invention there is provided a method for making such threaded locking devices that are especially suitable for nuts of the smaller sizes. Also the method is suitable for making such devices in large quantities on automatic machinery.

It will be obvious that various other modifications and changes in the details of the steps of the method described may be made by those skilled in the art within the principle and scope of the invention as expressed in the appended claims.

I claim:

1. The method for making a threaded locking device of the type described which method includes forming the body portion of the nut, forming a series of strips at one end of the body portion, reversely bending the strips to produce a section axially aligned with the body portion and of substantially the same internal diameter, tapping the nut, and thereafter again bending the strips.

2. The method for making a threaded locking device of the type described which method includes forming the body portion of the nut with a wall section extension at one end thereof, reversely bending the wall section to produce a portion axially aligned with the body portion and of substantially the same internal diameter, tapping the nut, and thereafter again bending the wall section.

3. The method for making a threaded locking device of the type described which method includes forming the body portion with a wall section extension at one end of the body portion cutting the wall section to form a plurality of strips substantially symmetrically disposed about the axis of the nut, reversely bending the strips to produce a portion axially aligned with the body portion and of substantially the same internal diameter, tapping the body and aligned portion of the nut, and thereafter again bending the strips to position the aligned portion with the thread thereof out-of-phase with the thread of the body portion.

4. The method for making a threaded locking device of the type described which method includes the steps of forming a body portion, with a cylindrical wall section extending from one end thereof, reversely bending the wall section to produce a portion substantially axially aligned with and of substantially the same internal diameter as the body portion, cutting through the portion of the wall section at spaced sections, tapping the body and aligned portions, and thereafter compressing the bent wall section to position the aligned portion with the thread thereof out-of-phase with the thread of the body portion.

5. The method for making a threaded locking device of the type described which method includes forming a nut body with a cylindrical extension at one end thereof, reversely and inwardly bending the extension to produce a portion axially aligned with and of substantially the same internal diameter as the body, reducing the thickness of the curved portion of the extension, tap-

ping the body and aligned portion of the extension, and thereafter compressing the nut.

6. The method for making a threaded locking device of the kind described which method includes the steps of forming a body portion with an axial opening therethrough and a relatively thinner wall section extending from one end thereof, reversely bending the wall section to produce a portion substantially axially aligned with the axial opening through the body portion, and tapping the body and aligned portions.

7. The method for making a threaded locking device of the kind described which method includes the steps of forming a body portion with an axial opening therethrough and a relatively thinner wall section extending from one end thereof, reversely bending the wall section to produce a portion substantially axially aligned with the axial opening through the body portion, tapping the body and aligned portions, and thereafter compressing the device to position the

aligned portions with the thread thereof out-of-phase with the thread of the body portion.
